UNITED STATES PATENT OFFICE.

GEORGE MACLOSKIE, OF SCHENECTADY, NEW YORK, ASSIGNOR TO GENERAL ELECTRIC COMPANY, A CORPORATION OF NEW YORK.

CONTROLLING MEANS FOR AIR-BRAKES.

No. 900,752.

Specification of Letters Patent. Patented Oct. 13, 1908.

Application filed March 5, 1908. Serial No. 419,284.

To all whom it may concern:

Be it known that I, GEORGE MACLOSKIE, a citizen of the United States, residing at Schenectady, county of Schenectady, State of New York, have invented certain new and useful Improvements in Controlling Means for Air-Brakes, of which the following is a specification.

My invention relates to the controlling means for braking systems controlled both electrically and pneumatically, such, for instance, as are described in my prior patents, No. 843,758, dated February 12th 1907, and No. 869,444, dated October 29, 1907.

Such systems are provided with a motor-man's valve for controlling the brakes pneumatically and with switch contacts for controlling the brakes electrically. It is convenient from an operating standpoint to arrange both the valve and the switch contacts so that they are operated by a single handle, but with the arrangements heretofore employed, it is objectionable from the standpoint of maintenance, since when the brakes are being controlled electrically the valve is moved back and forth on its seat without performing any useful function and undergoing needless wear which tends to produce leakage. For this reason it has sometimes been preferred heretofore to employ separate handles for the valve and contacts.

The object of my invention is to provide an arrangement whereby both valve and contacts may be operated from a single handle without producing any unnecessary wear on the valve. I accomplish this by so arranging the connections between the handle or operating member and the valve as to permit movement of said handle or member to operate the switch contacts without movement of the valve. More specifically stated, I insert in the connection between the operating member and the valve mutilated gears so arranged that the valve will remain stationary while the operating member is moved through a portion of its range.

My invention will best be understood by reference to the accompanying drawings, in which

Figure 1 shows an elevation of controlling means arranged in accordance with my invention, the cross-section being taken on the dotted line 1-1' of Fig. 2, which shows a plan view of the controlling means, with the

casing and operating spindle in cross-section; and Fig. 3 is a detail view of the mutilated gears.

In the drawings, A represents the valve for controlling the brakes pneumatically. This valve, which may be of any suitable construction, is connected to and operated by the spindle B. On this spindle is a mutilated gear C, which is engaged by a mutilated gear D on a second spindle E. This second spindle is shaped at its upper end in the usual manner, to receive a handle. Carried on the spindle E, and insulated therefrom, are the movable contacts F, which coöperate with the stationary contact fingers G to control the brakes electrically.

H represents a blow-out coil for the switch contacts.

As is best seen from Fig. 3, the mutilated gears are so arranged that the spindle E may be moved through a part of a revolution, to open and close the switch contacts, without moving the valve, while the movement of the spindle E over the rest of its revolution brings the teeth of gears D and C into mesh, so as to rotate the operating spindle B of the valve. The gears D and C are provided with bearing surfaces, as shown in Fig. 3, by which the valve is locked in position, except when the teeth of the two gears are in mesh.

I do not desire to limit myself to the particular construction and arrangement of parts here shown, but aim in the appended claims to cover all modifications which are within the scope of my invention.

What I claim as new, and desire to secure by Letters Patent of the United States, is,—

1. Controlling means for braking systems controlled both electrically and pneumatically, comprising a valve for controlling the brakes pneumatically, switch contacts for controlling the brakes electrically, a single operating member for said valve and said switch contacts, and connections between said valve and said member adapted to permit the movement of said member to operate said contacts without movement of said valve.

2. Controlling means for braking systems controlled both electrically and pneumatically, comprising a valve for controlling the brakes pneumatically, switch contacts for controlling the brakes electrically, a single operating member for said valve and said

contacts, and mutilated gears in the connection between said valve and said member, whereby said member may be moved to operate said contacts without movement of said 5 valve.

3. Controlling means for braking systems controlled both electrically and pneumatically, comprising a valve for controlling the brakes pneumatically, switch contacts for 10 controlling the brakes electrically, a single operating member for said valve and said switch contacts, connections between said valve and said member adapted to permit the movement of said member to operate said 15 contacts without movement of said valve, and means for locking said valve in position except when it is being moved by said member.

4. Controlling means for braking systems 20 controlled both electrically and pneumatically, comprising a valve for controlling the brakes pneumatically, switch contacts for controlling the brakes electrically, a single operating member for said valve and said 25 contacts, and mutilated gears in the connection between said valve and said member, whereby said member may be moved to operate said contacts without movement of said valve, said gears having bearing surfaces 30 faces adapted to lock said valve in position

except when the teeth of said gears are in mesh.

5. Controlling means for braking systems controlled both electrically and pneumatically, comprising a valve for controlling the 35 brakes pneumatically, an operating spindle therefor, a second spindle adapted to receive, and to be moved by, a handle, mutilated gears connecting the two spindles, and switch contacts for controlling the brakes electrically 40 carried by said second spindle.

6. Controlling means for braking systems controlled both electrically and pneumatically, comprising a valve for controlling the brakes pneumatically, and operating spindle 45 therefor, a second spindle adapted to receive, and to be moved by, a handle, mutilated gears connecting the two spindles, and switch contacts for controlling the brakes electrically carried by said second spindle, said 50 gears having bearing surfaces adapted to lock said valve in position except when the teeth of said gears are in mesh.

In witness whereof I have hereunto set my hand this 3rd day of March 1908.

GEORGE MACLOSKIE.
